L. SYKES.

THROTTLE VALVE FOR PNEUMATIC TOOL HANDLES.

APPLICATION FILED APR. 15, 1919.

1,367,570.

Patented Feb. 8, 1921.

UNITED STATES PATENT OFFICE.

LEWIS SYKES, OF CAMDEN, NEW JERSEY, ASSIGNOR OF ONE-HALF TO LEON G.
BUCKWALTER, OF MERCHANTVILLE, NEW JERSEY.

THROTTLE-VALVE FOR PNEUMATIC-TOOL HANDLES.

1,367,570.

Specification of Letters Patent.

Patented Feb. 8, 1921.

Application filed April 15, 1919. Serial No. 290,143.

To all whom it may concern:

Be it known that I, LEWIS SYKES, a citizen of the United States, residing in the city of Camden, county of Camden, State 5 of New Jersey, have invented a new and useful Throttle-Valve for Pneumatic-Tool Handles, of which the following is a specification.

In pneumatic tools of the prior art as 10 generally commercially constructed, it has heretofore commonly been the custom to locate in the grasping or other portion of the pneumatic tool handle, a valve bushing having a bore therethrough of uniform diameter and to locate within said bushing a 15 sliding throttle valve composed of two pistons or heads of uniform diameter joined by a neck, which pistons control the flow of motive fluid through the handle to the valve 20 and piston of the pneumatic tool.

While this construction may have the advantage of being cheaply manufactured, since, it may be somewhat cheaper to manufacture a bushing having its internal bore of 25 the same diameter throughout and it may also be somewhat cheaper to construct a throttle valve with two pistons of uniform diameter, I have found that in these tools, which are subject to considerable vibration 30 in use and are frequently subjected to considerable abuse by the workmen, a throttle valve of this character soon becomes leaky even when closed or supposed to be closed and is much less efficient than a throttle 35 valve of my novel construction hereinafter referred to.

For the purpose of obviating the disadvantages above enumerated, I have devised my present invention which relates to a 40 pneumatic tool handle generally employed in riveting, shipping, stone working, and analogous uses and consists of a novel construction of valvular mechanism, comprising a bushing of novel construction extending 45 throughout the entire grasping portion of the pneumatic tool handle and having an upper solid portion having therein an elongated bearing for the valve operating pin, said bushing having upper and lower heads, 50 the upper head being located near the middle of the bushing, which latter has outlet ports above said upper or central head and inlet ports below said upper or central head, said bushing being further provided 55 with a downwardly facing valve seat located

at a point directly above said inlet ports and having an upwardly seating and upwardly spring pressed ball valve coacting with said seat, the upper solid portion of said bushing above said outlet ports being accurately 60 bored or drilled so that said valve actuating pin or stem, which reciprocated therein and is depressed by a manually operated lever mounted in a slit in the upper portion of the grasping handle fits closely therein, 65 whereby leakage is reduced to a minimum and the flow of the compressed or other motive fluid under pressure from the supply hose to the valve cylinder is readily controlled through the medium of said ball 70 valve and its adjuncts, which valve instantly becomes seated when the operator removes his thumb or finger from said manually operated lever.

By my novel bushing construction, 75 wherein the valve stem or valve operating pin has an elongated bearing extending for considerable length in the upper solid portion of the bushing, leakage through the upper portion of the bushing is prevented, 80 irrespective of whether the valve is open or closed, and I in addition cause live air to constantly act on the bottom of the ball valve when seated, so that the tendency is for the valve to be always forced upwardly 85 against its downwardly facing valve seat, whereby said ball valve is always, when closed, pressed upwardly toward and against its seat by the combined pressure of the live 90 motive fluid and the coacting spring.

By my novel construction not only is the life of the throttle valve and its bushing generally prolonged, and leakage of the compressed air entirely prevented, which item in large industrial plants, such as shipyards, boiler shops and the like, where a 95 number of pneumatic tools of this general character are employed, is one of considerable importance, since the ball valve, in the handle will remain effectively seated under 100 normal conditions of non-use or when the pneumatic tool is inoperative, but in addition, since my valvular device consists of but two moving parts, to wit: the pin and ball valve, either or both of these can be replaced in case of wear or breakage, in a few 105 seconds time by an ordinary mechanic at the expense of a few cents, without necessitating the tool being laid up for repairs for any length of time, and in addition by pro- 110

viding a slot in the top of the bushing for the valve operating lever, I provide an effective guide for the lever cam which contacts with the valve operating pin.

5 To the above end, my invention consists of a novel construction of a pneumatic tool handle, bushing and ball valve therefor, wherein the valve operating pin has an elongated bearing in the upper solid portion of 10 the bushing and the valve seats upwardly against a downwardly facing valve seat and is under normal conditions always pressed upwardly against said seat by live air pressure from below, the valve being unseated 15 by a downward movement of a manually operated lever or its equivalent, whereby waste and leakage of the compressed air are avoided or reduced to a minimum.

It further consists of a novel construction 20 of pneumatic tool handle, bushing, ball valve therefor and their adjuncts, wherein the valvular mechanism comprising the valve and its stem are composed of only two parts, so that in case of wear, it is only 25 necessary to renew or replace that one of said parts which has become worn.

For the purpose of illustrating my invention I have shown in the accompanying drawing a typical embodiment of it, which 30 is at present preferred by me, since this embodiment will give in practice satisfactory and reliable results, although it is to be understood that the various instrumentalities of which my invention consists can be 35 variously arranged and organized and that my invention is not limited to the precise arrangement and organization of these instrumentalities, as herein shown and described.

40 Figure 1 represents a sectional view of a pneumatic tool handle showing a bushing therein, having its upper portion solid and providing an elongated bearing for the valve operating pin and a ball throttle valve embodying my invention, the valve being shown in closed position.

Fig. 2 represents a sectional view of a handle, bushing and its adjuncts, similar to Fig. 1, but showing the throttle valve in 50 open position and the valve pin or stem and manually operated lever in depressed position.

Fig. 3 represents a perspective view of a bushing and its adjuncts.

55 Similar numerals of reference indicate corresponding parts in the drawings.

Referring to the drawings:—

1 designates a pneumatic tool handle having an inlet chamber 2, which is located at 60 the lower outer portion of the handle and contains the nipple 3 for the compressed air hose, the compressed air or other motive fluid or fluid pressure passing through the inlet chamber 2 and the bushing ports 4 into 65 the lower valve chamber 5, which is located

in the lower portion of the bushing 6, the bottom of said bushing being closed by the threaded plug or closure 7, which serves as a support for the coiled spring or equivalent tension device 8, the bottom of which spring 70 is in contact with the top of said plug, while the upper end of said spring is in contact with the under side of the ball valve 9, which is positively pressed against the downwardly facing valve seat 10, through the medium of 75 said spring 8, it being apparent that when the valve 9 is seated as seen in Fig. 1, live air pressure in addition is continuously at all times acting on the bottom thereof. The upper portion of the bushing 6 is solid and 80 provided with a bore or air passage 11 therein, which is of less diameter than the ball valve chamber 5 below said bore 11, which terminates at the shoulder or point 12, below which are located the outlet ports 13, which 85 permit the escape of the motive fluid into the pressure supply duct 14. The bushing 6 is provided with the upper or substantially central head 15 and the lower head 16, the portion 17 between said heads being of somewhat reduced diameter as is also the portion 18 above said head 15. The upper portion 19 of the bushing is of lesser diameter than the portion 18, and is solid, as will be understood from Figs. 1 and 2, being provided with a 95 bore 20 therein, in which fits accurately the pin or valve stem 21, whereby the ball valve 9 is moved from its closed or seated position seen in Fig. 1 into its open or unseated position seen in Fig. 2.

22 designates a manually operated lever having the thumb piece 23 which is pivotally mounted at 24 in the slit 25 in the upper outer portion of the handle 1, and having the cam 26, which moves in the slot 26 in the top 105 of the bushing 6, said cam 26 bearing on the top of the pin 21 which fits nicely and accurately in the elongated bearing 20, so that in practice there is no leakage of motive fluid under any conditions, through the upper 110 solid portion 19 of the bushing. When the manually operated lever 22 is depressed from the position seen in Fig. 1 into the position seen in Fig. 2, it will be apparent that the ball valve 9 will be unseated and motive fluid 115 entering through the ports 4 and the bore 11 will flow through the ports 13 into the pressure supply duct 14 to the vitals of the riveting, clipping or other hammer 27 or the like. When the workman removes his pressure 120 from the thumb piece 23, the spring 8 will cause the valve to seat in the position seen in Fig. 1, and in addition the valve will be tightly held against its seat by the pressure of the live motive fluid under it.

125 It will be understood in practice that the heads 15 and 16 and the upper solid portion 19 of the bushing are so constructed as to fit with a drive fit within the grasping handle, said parts 15, 16 and 19 being coated with 130

shellac before being driven into position so that any expense of threading the bushing into the handle is entirely obviated, the valve mechanism comprising merely the bushing 6, the pin 21, the valve 9, spring 8 and the plug or closure 7.

As already explained in the old style of throttle valve, where the bushing has a bore of uniform diameter and the valve pistons 10 are of uniform diameter, in a comparatively short period, owing to the wear between said pistons and bushing, there is a constant leakage of compressed air even when the throttle valve is closed or supposed to be 15 closed, which it is especially desirable to prevent on account of the expense and waste involved, and, furthermore, during said waste and leakage, the motive fluid is liable to flow to the piston of the tool, frequently causing 20 the latter to accidentally start or fly out of the cylinder together with the tool bushing, rivet set or chisel or working tool, which may cause serious injury.

It will be apparent from the foregoing 25 that my novel bushing 6, constructed as described, together with my ball valve, valve operating pin, spring and closure, can be furnished as a unit, as seen in Fig. 3, so as to be readily fitted into existing tool handles.

30 I am aware of the construction seen in patents to Meissner, No. 626,497, and 636,810, wherein it has been proposed to employ a valve operating pin in conjunction with a multiplicity of springs, plungers, locks and 35 other contrivances, but said Meissner devices do not disclose a bushing constructed in accordance with my invention, nor do they disclose a ball valve collocated with such a bushing, as in my invention, nor do they disclose 40 a bushing extending throughout the length of the handle and provided with a solid upper portion, whereby an elongated bearing for the valve operating pin is provided, and my invention is consequently differentiated in the foregoing and other respects 45 from said Meissner patent.

I am also aware that it has heretofore 50 been proposed to employ ball valves in other locations, but so far as I am aware, I am the first in the art to employ a bushing of the character herein described, having its upper portion solid so as to provide an elongated bearing therein for the valve operating pin, in conjunction with a ball valve, a 55 downwardly facing valve seat, and inlet and outlet ports collocated as above described, and my claims to these features are to be interpreted in accordance with the scope accorded to inventions of this character.

60 Having thus described my invention, what I claim as new and desire to secure by Letters Patent, is:—

1. The combination of a pneumatic tool handle having a pressure supply duct leading 65 longitudinally through the grasping por-

tion thereof, a manually operated valve lever pivotally mounted in a narrow slit in the upper outer portion of said handle and capable of free and unobstructed forward movement at all times, a throttle valve bushing 70 extending throughout the grasping portion of said handle and having its upper portion solid and terminating at the upper and lower boundaries thereof, said bushing having upper and lower bores therein of varying 75 diameters, said lower bore being of greater diameter than said upper bore and said bushing having inlet ports in said lower larger bore and outlet ports leading from said upper smaller bore respectively, said 80 latter ports leading to the outlet portion of said pressure supply duct, a closure secured within the lower portion of said bushing, a downwardly facing valve seat located in said bushing at the junction of said bores, a ball 85 valve seating upwardly against said seat to close the latter, a spring supported upon said closure and acting on the bottom of said ball valve for normally holding said ball valve against its seat, a valve operating 90 pin of uniform diameter insertible in said bushing from either end and positioned above said ball valve, said valve pin having its lower end disconnected from said valve, and having an elongated bearing in the upper 95 solid portion of said bushing so as to prevent leakage therethrough, and a cam on said valve lever in direct contact with the top of said valve stem to depress the latter, said valve pin being retained between said ball 100 valve and cam.

2. In a pneumatic tool handle having a pressure supply duct leading longitudinally through the grasping portion thereof, a bushing located in said grasping portion and comprising the heads 15 and 16, the reduced areas 17 and 18 and the solid upward extension 19 having an elongated bearing therein, said bushing having a lower valve chamber, inlet ports leading to the upper portion of 110 said valve chamber, a closure for the bottom of said valve chamber, a downwardly facing valve seat located above said inlet ports, an upwardly seating ball valve for said valve chamber, a spring intermediate said closure 115 and ball valve, a passage above said valve chamber, said passage having outlet ports leading therefrom, a valve operating pin of uniform diameter having an elongated bearing in the upper solid portion of said bushing, and a manually operated pin actuating lever pivoted in the upper outer portion of 120 said handle, said lever having a cam thereon contacting with the top of said pin, the top of said bushing being slotted so as to provide ways in which the under side of said lever and its pin-actuated cam oscillates.

3. As an improved article of manufacture, the herein described unit adapted for insertion in a pneumatic tool handle, comprising 130

a bushing 6 having the heads 15 and 16 and the portion 17 of reduced diameter between said heads, a portion 18 above said head 15 of reduced diameter, and a solid elongated portion 19 above said portion 18 and of lesser diameter than the latter, said bushing having a lower valve chamber 5 and a bore 11 above said valve chamber and being provided with the inlet ports 4 and the outlet ports 13 and the elongated bearing 20, a

valve operating pin 21 in said bearing, a downwardly facing valve seat located between said inlet and outlet ports, a ball valve 9 in said valve chamber, a closure 7 in the lower portion of said bushing, and a spring 15 intermediate said ball valve and closure.

LEWIS SYKES.
